UNITED STATES PATENT OFFICE.

MARGARET M. CLARK, OF NEWPORT, PENNSYLVANIA.

MAILING-PACKAGE.

1,130,889.

Specification of Letters Patent.

Patented Mar. 9, 1915.

Application filed June 26, 1914. Serial No. 847,494.

To all whom it may concern:

Be it known that I, Mrs. MARGARET M. CLARK, a citizen of the United States, residing at Newport, in the county of Perry and State of Pennsylvania, have invented certain new and useful Improvements in Mailing-Packages, of which the following is a specification.

My invention relates to a package and 10 more particularly to a mailing package.

The primary object of my invention resides in the provision of a package formed of substantially stiff material and suitably reinforced for receiving small articles for 15 transportation through the mail, the package having novel means formed thereon for removably holding the same in a closed position.

Another object of my invention resides in 20 the provision of a novel mailing package formed from a blank having novel means associated therewith for removably holding the same in a folded position, the holding means being associated with reinforcing 25 means on the body of the blank for facilitating the efficient use of the package.

A further object of my invention resides in the provision of a novel holding means 30 removably mounted on the blank and associated with the reinforcing means on the blank for securely holding a small article within the package formed when the blank is folded or assembled.

A still further object of my invention resides in the provision of a device of the 35 character described that is simple in construction, efficient in operation and one that can be manufactured and placed on the market at a minimum cost.

40 Other objects as well as the nature, characteristic features and scope of my invention will be more readily understood from the following description taken in connection with the accompanying drawings and 45 pointed out in the claims forming a part of this specification.

Referring to the drawings:—Figure 1 is 50 a top plan view of my invention when folded; Fig. 2 is a bottom plan view of my invention folded; Fig. 3 is a top plan view of the blank from which the package is

formed; and Fig. 4 is a longitudinal central sectional view of my invention when folded.

Referring more particularly to the drawings in which similar reference numerals designate like or corresponding parts throughout the different views, I provide a substantially triangular blank formed preferably of stiff paper, the blank comprising 60 a substantially triangular body 1 which has extending from the elongated sides thereof side flaps 2 and 3. The flaps are of a triangular shape similar to the shape of the body 1 and are foldable on the creases 4 65 upon the body to provide a package and which side flaps are further provided with transversely extending slots 5, the latter being arranged adjacent the extreme pointed end of the flaps and arranged in spaced parallel relation with the outer side or base of the triangle as clearly shown in the drawings. The flaps when folded are positioned in alinement and receive the extreme pointed ends of the flaps and body portion, 75 which, when folded on the creases 6 constitute a tongue 7. In order to close the opposite end of the package, I have extended a substantially rectangular flap 8 from the short side of the side flap 3, the flap having 80 detachably secured therein a metallic locking clip 9 which in this instance consists essentially of a substantially T-shaped blank of bendable metal comprising a tongue 10 and arms 11. The clip is insert- 85 able in the parallel spaced slots 12 positioned substantially intermediate the ends of the flaps 8 and arranged in parallelism with the sides thereof and which arms are, for the purpose of more securely holding 90 the clip in position, inserted through the slots 13 positioned in parallel spaced relation with the outer end of the flap 8. The slots 13 are placed in registration with the slots 12 by folding the outer corners of the 95 flap 8 on the diagonally extending creases 14 to form a substantially triangular shaped flap 15 which is foldable on the crease 16 for facilitating the insertion of the flap into the transversely extending elongated slot 17 100 arranged in parallel relation adjacent the outer edge of the body.

For the purpose of reinforcing the body when the flap 16 is inserted within the slot 17 and in order to securely hold the triangular flap 15 against accidental displacement from the body, I have disposed upon the inner face of the body adjacent the open end thereof a reinforcing strip 18, the latter having its side and outer edges arranged in close parallel relation with the side and outer edges of the body and has the inner edge thereof arranged in parallelism with the crease 6 as clearly shown in the drawings. The strip 18 is further provided adjacent its outer edge with an elongated slot 19 for registration with the slot 17 in the body with a slot 20 arranged in parallel relation with the slot 19 adjacent the opposite end thereof, the slot 20 registering with the slot 21 in the body and which slots receive the tongue 10 of the metallic clip 9 for securely holding the flap 15 in position.

In assembling the blank to provide the package, said flap 2 is first folded on the crease upon the body 1 and the side flap 3 is now folded on the crease 4 upon the side flap 2 so that the slots 5 are positioned in alignment whereupon the pointed ends of the side flaps 2 and body 1 of the substantially isosceles shaped triangle are folded upon the creases 6 to provide a substantial tongue 7 for insertion within the slots for closing one end of the package. The arms 11 of the metallic clip 9 are now inserted in the slots 12 of the flap 8, the outer edges of which are now folded upon the diagonally arranged creases 14 and the arms 11 engaged in the slots 13 for facilitating the securing of the clip in position. The triangular flap 15 is now folded upon the crease 16 in a direction opposite to the direction in which the tongue 7 is folded and inserted in the alining slots 17 and 19 in the body and strip 18 respectively. In order to securely hold the tongue 15 within the alining slots 17 and 19, the tongue 10 of the clip 9 is extended through the slots 20 and 21 in the reinforcing strip and body respectively and bent toward the outer end of the package to constitute a substantial hook for the purpose set forth.

Although I have shown and described the preferred embodiment of my invention, I desire to be understood that I am not limited to the exact details shown, however, I desire that great stress be laid upon the provision of a reinforced blank, the blank being foldable and having novel means associated with a tongue extending therefrom for securely holding the tongue in a locked position.

From the above description taken in connection with the accompanying drawings, it can easily be seen that I have provided a device that is simple in construction contain-

ing but a few simple parts that can be cheaply manufactured and assembled and when assembled can be placed upon the market and sold at a minimum cost.

It will be understood that the above description and accompanying drawings comprehend only the general and preferred embodiment of my invention and that various minor changes in detail of construction, proportion and arrangement of the parts may be made within the scope of the appended claims and without sacrificing any of the advantages of my invention.

Having thus fully described my invention, what I claim as new and desire to secure by Letters Patent, is:

1. A wrapper including a triangular body, complementary side flaps extending from the margins thereof and folded upon the body to provide a package, a tongue formed by folding the vertices of the body and flaps upon themselves, said tongue being insertible in the registering slots in the flap for closing one end of the package, a rectangular tongue formed on the base of one of said flaps, a metallic clip associated therewith, said rectangular flap being foldable into a triangular form to reinforce said clip, said last mentioned tongue being insertible in a slot in said body, and said clip being locked in the slot in said body for closing the opposite end of the package.

2. A wrapper including a triangular body, complementary side flaps extending from the opposite margins thereof and folded upon the body to provide a package, a tongue formed by folding the vertices of said body and side flaps upon themselves, said tongue being insertible in the registering slots in the flaps for closing one end of the package, a reinforcing strip secured to the inner surface of the body conforming substantially to the contour thereof, said body being provided with registering slots, a rectangular tongue formed on the base of one of the side flaps, a metallic clip associated therewith, said rectangular flap being foldable into a triangular form to facilitate the securing of said clip, said last mentioned tongue being insertible in one of the registering slots in the body and strip, and said clip being locked in the other of the slots in the body and the strip for closing the other end of the package.

3. A wrapper including a triangular body, said flaps extending therefrom and foldable upon the body to provide a package, means for closing one end of the package, a rectangular flap formed upon one of the side flaps at the opposite end of the package, a T-shaped metallic flap associated with the rectangular tongue, said clip including oppositely extending arms and a tongue, the

arms being insertible in slots in the rectangular tongue, said rectangular tongue being foldable into a triangular form and again engageable with the arms of the clip for facilitating the securing of the clip, said triangular tongue being insertible in the slot in the body, and the tongue of said clip being arranged in locked engagement

with another slot in the body for closing the opposite end of the package.

In testimony whereof I affix my signature in presence of two witnesses.

MRS. MARGARET M. CLARK.
